UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A CREAM, SUGAR, AND BUTTER SET.

47,573.

Specification for Design.

Patented July 13, 1915.

Application filed October 10, 1914. Serial No. 866,149. Term of patent 3½ years.

To all whom it may concern:

Be it known that I, ANDREW J. SANFORD, a citizen of the United States, residing at Newark, Ohio, have invented a new, original and ornamental Design for a Cream, Sugar, and Butter Set, of which the following is a specification, reference being had to the accompanying drawing, forming part thereof.

Referring to the drawing, which is a perspective view of the design embodying my invention, the lower compartment A may be used for sugar; the intermediate compartment B for cream, and the top C for butter.

I claim:

The ornamental design for a cream, sugar and butter set, substantially as shown and described.

ANDREW J. SANFORD.
